UNITED STATES PATENT OFFICE.

HARRY NEWMAN, OF NEWARK, NEW JERSEY.

DESIGN FOR A BOTTLE.

Application filed July 3, 1928. Serial No. 27,369. Term of patent 7 years.

To all whom it may concern:

Be it known that I, HARRY NEWMAN, a citizen of the United States, residing at Newark, N. J., in the county of Essex and State of New Jersey, have invented a new, original, and ornamental Design for a Bottle, of which the following is a specification, reference being had to the accompanying drawing, forming part thereof.

Figure 1 is a front elevational view of the bottle, showing my new design.

Figure 2 is a side elevational view of the same.

Figure 3 is a rear elevational view of the same.

I claim:

The ornamental design for a bottle as shown.

HARRY NEWMAN.
